UNITED STATES PATENT OFFICE.

JOSEPHS G. HUOT, OF MONTREAL, QUEBEC, CANADA.

SHUTTER-BOWER.

1,164,523.

Specification of Letters Patent. Patented Dec. 14, 1915.

Application filed August 31, 1915. Serial No. 48,212.

To all whom it may concern:

Be it known that I, JOSEPHS G. HUOT, a subject of the King of Great Britain, and resident of the city of Montreal, in the Province of Quebec and Dominion of Canada, have invented certain new and useful Improvements in Shutter-Bowers, of which the following is a full, clear, and exact description.

10 This invention relates to improvements in shutter bowers, or as they are sometimes called, casement adjusters, and the object of the invention is to provide a device of this character which will be extremely smooth and steady in operation, and which will not buckle when force is applied to telescope the same from its full extended position.

20 A further object is to provide a simple and inexpensive device which will not readily wear out, and in which the resistance to movement may be readily adjusted.

The device consists essentially of a tube or barrel within which a plunger operates. One end of the barrel is pivotally connected 25 to a window sill and the opposite end of the plunger to the casement. When the casement is moved, the plunger is reciprocated in the barrel, and this reciprocation is resisted by friction of a clutch carried by 30 the plunger, so that the casement will be held in any position, to which it is set. The plunger consists of a rod, carrying on its end within the barrel, a clutch, formed of a number of leaves of spring metal compressed 35 within the barrel in such a way as to grip practically the entire circumference of the barrel.

40 In the drawings which illustrate the invention: Figure 1 is a side elevation of the device showing the barrel in section. Fig. 2 is a plan view of the clutch. Fig. 3 is a plan view showing the inner surface of one of the clutch parts. Fig. 4 is an enlarged end view of the plunger and clutch. Fig. 5 is an enlarged fragmentary sectional view 45 of one of the clutch parts, on the line 5—5, Fig. 3. Fig. 6 is a view of the various blanks before bending and assembling to form one of the clutch parts.

50 Referring more particularly to the drawings, 11 designates a tube or barrel pivotally

mounted at one end on a support 12, which may be attached to a window sill and provided at the opposite end with a centrally apertured cap 13 through which the rod 14 of the plunger passes. The end of the rod within the plunger is provided with a clutch comprising a pair of expansible members 15 and 15^a, and the opposite end is pivotally secured to a support 16 which may be attached to a casement or shutter.

Each part of the clutch consists of a plurality of leaves, designated 17, 17^a, 17^b, 17^c, the leaf 17 being outermost. These leaves decrease in width from the outermost to the innermost, as clearly shown in Figs. 3, 4 and 6, while all are of the same length, with the exception of the outer leaf 17 which is slightly longer than the others, so that the ends thereof may be bent in, as shown at 18, 70 to facilitate introduction of the clutch into the barrel. The outer clutch member is provided at each end midway between the side edges with a pair of cuts 19 forming a tongue 20, and each of the inner leaves 17^a, 75 17^b, 17^c are provided on the ends with notches adapted for the passage of the tongues 20 therethrough. The notches 21 of the leaves 17^a and 17^c are carried to such a depth that they terminate substantially in 80 line with the roots of the tongues 20, but the notches 22 of the leaf 17^b are carried much deeper into the material, so that they at least extend into line with the end of the tongue when folded back on the material of 85 the outer leaf. These notches 22 may also be slightly wider than the notches 21. If desired, cuts 23 may be formed in the leaf 17^c in line with the sides of the notches 21, thus forming tongues 24 at the bottoms of 90 the notches.

When the blanks have been cut to the shape shown in Fig. 6 from spring metal, preferably hard bronze on account of its corrosion resisting characteristics, they are 95 bent around their longitudinal axes to a suitable curvature, and are assembled in the order shown, so that the notches 21 and 22 are all in register and in line with the tongues 20, which are then bent through the notches, 100 so as to hold all the leaves together. The tongues 20 are then clenched down hard, and

force the tongues 24 of the leaf 17^c down into the leaf notches 22 of the leaf 17^b, until the tongues 24 of leaf 17^c come into engagement with the leaf 17^a, and the tongues 20 of the leaf 17 lie flush with the surface of the leaf 17^c, as will be clearly understood by reference to Fig. 5. It will be understood that when the leaf 17^c is formed with the cuts 23 and tongues 24, the notches 22 of leaf 17^b need not be wider than the notches 21, but that if the leaf 17^c is formed without these cuts, and tongues, the notches 22 of leaf 17^b will require to be of slightly greater width than the notches 21 in order to accommodate the displaced metal of the leaf 17^c. It will also be understood that the leaf 17^a must not be construed as limited to a single leaf, since this leaf represents any desired number of leaves inserted between the leaf 17 and the leaf 17^b, or if a very weak spring is desired, the leaf 17^a may be omitted altogether. It will thus be seen that if complete, the clutch member is provided with a notch 25 at each end. Pins 26 are driven through the plunger at suitable intervals apart, and project beyond the plunger slightly less than the thickness of the clutch members, so that when the clutch members are placed in position around the plunger, the notches 25 thereof will embrace the pins 26 of the plunger and hold the clutch members against longitudinal and rotary movement independent of the plunger.

While the clutch has been shown to consist of a pair of members, it is obvious that if desired, a single member of substantially cylindrical form, or three or more members similar to those shown in Figs. 2 and 3, but appropriately narrower, may be used.

As shown in Fig. 4, the curvature of the clutch members is of slightly greater radius than the curvature of the barrel, so that the clutch members will require to be sprung in order to insert them in the barrel, thus insuring considerable expansive pressure within the barrel. In curving the clutch member leaves, the radii of the leaves may be shortened from the outer to the inner, so that when assembled, the curvature of the leaves will be from a common center, or the curvature of all leaves may have equal radii, so that when the leaves are assembled and clamped together, the inner leaves will exert an appreciable expansive pressure on the outer leaves. Such a structure will result in forming a much stiffer spring in each clutch member, although the appearance of the assembled clutch members will be exactly the same.

Having thus described my invention, what I claim is:—

1. In a device of the character described, a barrel, a plunger slidable therein, and a clutch carried by the plunger comprising a

plurality of independent parts each built up of a series of resilient curved leaves, the curvature of said leaves being of greater radius than the curvature of the barrel.

2. In a device of the character described, a barrel, a plunger therein, a clutch mounted on the plunger comprising a plurality of independent parts, each composed of a series of resilient leaves decreasing in width from the outer to the inner. 70 75

3. In a device of the character described, a barrel, a plunger therein, a clutch on the plunger formed of a plurality of resilient leaves, curved approximately in conformity with the curvature of the barrel and decreasing in width from the outer to the inner, and means integral with one of said leaves holding all the leaves together. 80

4. In a device of the character described, a barrel, a plunger therein, a clutch on the plunger retained in compression by the barrel and frictionally engaging the inner surface of the barrel, said clutch comprising a series of thin resilient leaves decreasing in width from the outer to the inner, and means for holding the clutch against rotary or longitudinal movement independently of the plunger. 85 90

5. In a device of the character described, a barrel, a plunger therein, a clutch surrounding the plunger and held in compression by the barrel, said clutch comprising a plurality of resilient leaves of varying width notched at their ends and arranged with the notches thereof in register, and projections on the plunger engaging said notches and holding the clutch against rotary and longitudinal movement independently of the plunger. 95 100

6. In a device of the character described, a clutch member comprising a series of cylindrically curved superposed leaves decreasing in width from the outer to the inner, tongues integral with the ends of the outer leaf folded over the ends of the remaining leaves to hold all leaves together, the inner leaf having notches in the end thereof for the reception of portions of the inner leaf displaced by bending down of the outer leaf tongues. 105 110 115

7. In a device of the character described, a clutch member comprising a plurality of superposed leaves, tongues formed integral with the outer leaf and bent inwardly over the ends of the remaining leaves, and means provided for the reception of said tongues whereby the same will overlap the inner leaf and be flush with the surface thereof. 120

8. In a device of the character described, a clutch comprising a plurality of superposed leaves, the outer leaf having at each end an integral tongue cut from the material thereof and the remaining leaves being notched at each end for the reception of said tongues, the notches of an intermediate leaf 125 130

being deeper than the notches of other leaves, and tongues integral with the inner leaf formed at the bottoms of its notches and displaced into the deeper notch of the 5 intermediate leaf by the tongues of the outer leaf.

In witness whereof, I have hereunto set my hand, in the presence of two witnesses.

JOSEPHS G. HUOT.
